UNITED STATES PATENT OFFICE.

SOREN JENSEN, OF LOS ANGELES, CALIFORNIA, ASSIGNOR OF ONE-HALF TO OSCAR THEODORE GROVER, OF LOS ANGELES, CALIFORNIA.

PENCIL-SHARPENER.

1,130,294.

Specification of Letters Patent.

Patented Mar. 2, 1915.

Application filed October 20, 1913. Serial No. 796,196.

To all whom it may concern:

Be it known that I, SOREN JENSEN, a citizen of the United States, residing at Los Angeles, in the county of Los Angeles, State 5 of California, have invented new and useful Improvements in Pencil-Sharpener, of which the following is a specification.

My invention relates to manually operated pencil sharpeners, and relates more particularly to improvements on that class of pencil sharpeners as set forth in United States Letters Patent No. 965,907, issued to me on August 2, 1910, and one of the principal objects of the invention is to provide an improved 15 sharpener having fewer parts than that shown in my patent heretofore mentioned, and which is simple in construction and efficient in operation.

It is also an object to provide a pencil 20 sharpener which slides upon the pencil and is always present for operation.

It is also an object to provide a pencil sharpener, which, when placed on the pencil will prevent the latter from rolling and afford a convenient finger hold or rest in using the pencil.

It is a further object to provide a pencil sharpener in which the sharpening medium may be readily replaced without the use 30 of tools or machinery.

In the drawings accompanying this specification: Figure 1 shows a pencil with the sharpener, showing its application as a finger rest. Fig. 2 is a perspective view of the blade holding sleeve with the blade removed. Fig. 3 is a perspective view of the blade alone. Fig. 4 is a similar view of the two parts assembled in operative position. Fig. 5 is a view showing the method of holding 40 the sharpener to sharpen the pencil therewith.

More specifically in the drawings, 6 designates the improved pencil sharpener which is shown as mounted in its normal inoperative position upon a pencil 7, as clearly shown in Fig. 1, and this sharpener consists mainly of a substantially tubular structure formed of sheet metal in which a plurality of slots are formed and the parts bent upon 50 themselves intermediate certain cut-away portions on the edges thereof to form the clamping members 10 and 11, and intermediate of these on the oppositely disposed side from that where the edges of the integral blank forming the sleeve are brought

together are the slots. Taking them in order from the clamping member 10 a slot 12 is formed into which the sharpened edge 14 of the blade 8 projects and through which the pencil is introduced in the sharpening 60 process. Separating the slot 12 from that designated 13 is a bridge 15 formed with sides and a flat transverse guard and adapted to straddle over and embrace the elongated blade 8, the transverse bar on the bridge 65 engaging with the upper or outer side of the blade while the ears 16 formed just behind the bridge 15 engage the opposite side of the blade and form a seat therefor.

The slot 13 is rectangular in form, being 70 not only intersected by the ears 16 but projecting in the axial line of the structure is the spring tongue 17 which bears upon the under or inner side of the blade, the tongue 75 being provided with a slot 18 through which the lug 19 formed on the blade 8 is projected.

Intermediate the portion of the inner end 80 of the tongue 19 and the very remote portion provided with the slot 18, an indentation or depression 21 is formed against which the shoulder 22 on the blade abuts, the tension of the tongue 17 holding the shoulder securely in the slot 18 and binding 85 the blade sufficiently between the transverse bar of the bridge 18 and the ears 16 to form a good hold.

In the operation of the device the end of 90 the pencil to be sharpened is inserted from the side provided with the slots in through the slot 12 and in contact with the blade 8, the thumb and first finger grasping the sleeve around the clamp portion 10 and the portions of the sleeve 23 intermediate the bridge 15 and the clamp 10.

What I claim is:

1. A pencil sharpener, comprising a tubular body member formed with a pair of longitudinally extending slots on one side 100 thereof, a bridge separating said slots, a removable blade extending beneath said bridge with its cutting edge arranged across one of the slots in the body member, ears projecting from the sides of the other slot 105 beneath the blade, integral means on the body member for detachably engaging the blade, comprising a spring tongue having a slot therein, and a finger on the blade engageable with said slot.

2. A pencil sharpener, comprising a body 110

- member adapted to slide upon a pencil having a longitudinally extending slot therein, a bridge member formed thereon, a spring tongue extending toward the bridge having a slot therein, a removable blade extending beneath the bridge with its cutting edge arranged across the slot, a finger on said blade engageable with the slot in the tongue, whereby the blade is held in position.
- 10 3. A pencil sharpener, comprising a body member adapted to slide on a pencil and formed with pencil clamping members and having a longitudinally extending slot, a bridge member, a pair of inturned ears adjacent said bridge member, a curved spring tongue formed with a shoulder and having a slot therein extending toward the ears, and a removable blade having a finger thereon engageable with the slot in the tongue, and
- 15 shoulders engageable with the shoulders on the tongue, said blade supported on said ears and extending beneath the bridge member.
- 20

4. A pencil sharpener, comprising a body member formed substantially as a sleeve arranged to slide upon a pencil and clamped thereon having a plurality of slots therein, two of said slots being separated by a bridge and having a resilient tongue with a slot therein projecting longitudinally toward said bridge, ears formed on the sides of the slot, and a sharpening blade having a finger formed on its end oppositely disposed from the sharpened end thereof, said finger being inserted in the slot in said tongue and engaging said bridge and said ears and resiliently held in position by said tongue, the whole when fastened upon a pencil adapted to form a finger rest.

In witness that I claim the foregoing I have hereunto subscribed my name this 13th day of October, 1913.

SOREN JENSEN.
